B. HUBER.
CYLINDER PRINTING PRESS.

No. 416,786.

Patented Dec. 10, 1889.

UNITED STATES PATENT OFFICE.

BERTHOLD HUBER, OF TAUNTON, MASSACHUSETTS, ASSIGNOR TO THE HUBER PRINTING PRESS COMPANY, OF SAME PLACE.

CYLINDER PRINTING-PRESS.

SPECIFICATION forming part of Letters Patent No. 416,786, dated December 10, 1889.

Application filed August 31, 1889. Serial No. 322,541. (No model.)

To all whom it may concern:

Be it known that I, BERTHOLD HUBER, of Taunton, county of Bristol, State of Massachusetts, have invented an Improvement in 5 Cylinder Printing-Presses, of which the following description, in connection with the accompanying drawings, is a specification, like letters on the drawings representing like parts.

10 This invention is an improvement on that described in United States Patent No. 370,789, dated October 4, 1887. In the said patent the impression-cylinders, which rise and fall at intervals, are so geared together that the second impression-cylinder derives its rotation from a toothed gear on the first impression-cylinder, which engages a like gear on the second impression-cylinder, the gear on the first impression-cylinder being driven by a 15 smaller driving-gear. In the said machine, as the first impression-cylinder rises and falls, its teeth are made to enter more or less into engagement with the teeth of the driving-gear. This variation in the engagement of 20 the teeth of these gears, due to the rising and falling of the impression-cylinders, causes a certain amount of backlash, which interferes with the accuracy of register of the second impression-cylinder. To overcome this difficulty, I have provided the press with gears 25 whereby each cylinder, besides being geared together, is driven positively from the same source of motion, thereby insuring absolutely correct registration of the second impression-30 cylinder.

35 My invention consists, essentially, in the combination, with the first and second impression-cylinders and their attached gears in mesh with each other, of a driving-gear to drive one of the said cylinders, and an independent intermediate gear between the said driving-gear and the other of the said impression-cylinders, whereby the said cylinders are each positively driven at the same speed, the gears carried by the said cylinders being kept in mesh and aiding in preserving 40 steadiness of movement.

Figure 1 in side elevation represents a sufficient portion of the press shown in the patent referred to with my present improvements added to enable my invention to be

understood. Fig. 2 is a section in the line *x*, Fig. 1. Figs. 3 and 4 are enlarged details of the gearing shown in Figs. 1 and 2, Fig. 3 showing the second cylinder lifted, and Fig. 4 the first cylinder lifted, and Fig. 5 is a modification in which the driving and intermediate gears engage the toothed wheels of the cylinders, which are in direct engagement with each other.

The frame-work *A A'*, the bed *B'*, the impression-rolls *C' C²*, the toothed gears *C³ C⁴*, attached, respectively, thereto, the toothed gear *D⁸* in mesh with a gear carried by the first impression-cylinder and engaging a gear 55 *D⁷*, fast upon and rotating the reversing-shaft *D²*, the swivel-box *D³*, the box *D⁴*, adapted to rise and fall in the slotted bracket *D⁵*, the roller *D⁶* at the inner end of the said reversing-shaft, the rack *B⁴*, the reversing-pinion 60 *D'*, the eccentrics *I³ I⁴* at opposite ends of the shafts to which they are connected, the said shafts being extended across the machine and having like eccentrics at each end thereof, the lifting bars or rods *N' N²*, supporting, respectively, the journals of the first and second impression-cylinders, the feed-board *F*, and the fly *F'*, are and may be all as common to the patent referred to, wherein like letters are employed to designate like parts. In the 65 accompanying drawings I have omitted the devices for actuating the shafts carrying the said eccentrics, as they will be the same as in the patent referred to.

Herein the power-shaft *A³* (shown as a short 70 sleeve supported by a suitable stud *A⁴*) has a pinion *3*, (shown by full lines, but partially in section, Fig. 2, and by dotted lines, Fig. 1,) which directly engages the gear *D⁸*, which in this my present invention I have made as the 75 driving-gear to impart motion to both impression-cylinders. To do this, in Figs. 1, 2, 3, and 4 I have provided the impression-cylinder *C'* with a toothed gear *a* and the impression-roll *C²* with a toothed gear *b*, the driving-gear *D⁸* directly engaging the toothed gear *a* and rotating the impression-cylinder 80 *C'*. The driving-gear *D⁸* also engages an intermediate gear *b'*, mounted to rotate about a stud *b²*, carried on the frame by a hub projecting through the lifting-bar *N²*, the said intermediate gear engaging the toothed gear 85 *b*.

b, referred to. In this way, as the driving-gear D^8 is rotated, it positively rotates the impression-cylinder C' and rotates the intermediate gear b' , causing it to positively rotate the impression-cylinder C^2 .

5 In operation, when the impression-cylinder C' is in its lowest position, the impression-cylinder C^2 will be elevated, and referring to Fig. 3, which is a diagram illustrating the 10 position of the gearing with the cylinders in the position stated, it will be seen that the gear a is in full mesh with the driving-gear D^8 , and that the gear b is but partially in mesh with the intermediate gear b' . In this 15 condition the driving-gear D^8 becomes the prime driver for both impression-cylinders, the motion being transmitted from the said driving-gear through the gears a C^3 C^4 , the intermediate gear b' also aiding in such motion.

20 Referring to Fig. 4, another diagram, it will be supposed that the impression-cylinder C' is elevated and the impression-cylinder C^2 is down, and in this condition it will be seen that the gear b is in full mesh with the gear b' and that the gear a is in but partial mesh with the driving-gear D^8 , and in this condition the impression-cylinder C' is driven mainly by the driving-gear working through 25 the intermediate gear b' , the gear b , and the gear C^4 , it engaging the gear C^3 fast on the impression-cylinder C' , the said driving-gear D^8 aiding, however, in imparting motion to the said first impression-cylinder. In this 30 way it will be seen that the difference in mesh between the several gears, owing to the rise and fall of the impression-cylinder, does

not permit of any slip or lost motion or backlash, and as a result the second impression-cylinder always comes in proper register at 40 the proper time.

As a modification of my invention I may omit the toothed gears a b , which are attached to the toothed gears C^3 C^4 , and cause the driving-gear D^8 to directly engage the toothed 45 wheel C^3 , the intermediate gear b' directly engaging the toothed gear C^4 . This modification is represented by the diagram, Fig. 5.

I claim—

1. The combination, with the first and second impression-cylinders and their attached gears in mesh with each other, of a driving-gear to drive one of the said cylinders, and an intermediate gear between the said driving-gear and the other cylinder-gear, whereby 55 the said cylinders are each positively driven at the same speed, substantially as described.

2. The combination, with the first and second impression-cylinders, each having a large and small cylinder-gear mounted thereon, the two large gears being in mesh with each other, of a driving-gear to drive one of the small cylinder-gears, and an intermediate gear between the said driving-gear and the other small cylinder-gear, whereby the said 65 cylinders are each positively driven at the same speed, substantially as described.

In testimony whereof I have signed my name to this specification in the presence of two subscribing witnesses.

BERTHOLD HUBER.
